UNITED STATES PATENT OFFICE.

FREDRIK LJUNGSTRÖM, OF BREVIK-LIDINGÖN, AND ISIDOR BROBERG, OF TALLHYDDAN LIDINGÖN, SWEDEN, ASSIGNEES TO AKTIEBOLAGET LJUNGSTRÖMS ANGTURBIN, OF STOCKHOLM, SWEDEN, A CORPORATION.

LOCOMOTIVE CONDENSER.

1,407,072.

Specification of Letters Patent. Patented Feb. 21, 1922.

Application filed January 7, 1920. Serial No. 350,013.

To all whom it may concern:

Be it known that we, FREDRIK LJUNGSTRÖM and ISIDOR BROBERG, subjects of the King of Sweden, residing, respectively, at Brevik-Lidingön, Sweden, and Tallyhyddan, Skärsätra, Lidingön, Sweden, have invented a new and useful Locomotive Condenser, of which the following is a specification.

10 The present invention relates to arrangements in locomotive condensers and principally refers to the location of the cooler and that of the receptacle for the water of condensation, condensers of an elongated 15 shape provided with cooling elements extending transversely thereof being particularly considered.

The invention primarily consists therein 20 that the steam supply pipe is disposed in the centre of the condenser, or approximately so, extending longitudinally thereof, the said pipe forming a supporting frame for the cooling elements, which latter incline downwardly toward the sides of the condenser 25 where they are connected with two collecting pipes for the water of condensation, one of such collecting pipes being disposed on either side of the condenser.

The invention also consists in the two collecting 30 pipes for the water of condensation being connected with one another, or with the steam supply pipe, by means of two hollow stays of such material as to render the expansion of the stays and that of the 35 elements coincident.

The invention further consists therein 40 that the fans required for producing a circulation of the air are disposed on the steam supply pipe of the cooling elements so that they will force the air to flow in an upward direction.

The invention still further consists in the 45 collecting pipes being connected with the steam receptacle by means of branch pipes which, together with the supply pipe, carry the air cooler.

In the accompanying drawing wherein 50 the preferred embodiment of the invention is illustrated,

50 Fig. 1 is a vertical transverse sectional view through the condenser.

Fig. 2 is a side elevation thereof, and

Fig. 3 is a top plan view.

Referring to the drawing in detail, 1 indi-

cates the receptacle for steam and water of 55 condensation, said receptacle being of elongated cylindrical form. The receptacle 1 is provided with an inlet 16 for steam and an outlet 17 for the water. The cooling elements 2 extend transversely of the condenser and are located between the steam supply pipe 3 and the conducting pipes 4 for the water of condensation. The pipe 3 forms a support for the upper ends of the elements 2 and the pipe 3 is supported upon 60 the receptacle 1 by pipes 8 by which steam is conducted to the pipe 3. The collecting pipes 4 are connected with each other or with the supply pipe 3 by means of hollow stays 5 and with the steam space of the receptacle 1 by means of branch pipes 6 which latter, together with the steam pipe 3, carry the air cooler. In order to render accessible the elements 2 which latter incline from the center of the condenser downwardly toward the sides thereof, the condenser is provided with a platform or bridge 7 arranged above the steam supply pipe 3. As will appear from Fig. 1 the steam having 75 entered the receptacle 1 through the inlet 16 ascends in part through the pipes 8 to the pipe 3 and from the latter pipe the steam enters the cooling elements 2 which latter are preferably so constructed as to provide 80 a relatively wide radiating surface. The products of condensation flow down the elements 2 into the collecting pipes 4 and finally through the pipes 6 into the receptacle 1.

The stays 5 consists preferably of pipes 90 one end of which is connected with one pipe 4. The other end of each pipe 5 is, as shown in Fig. 1, connected with the pipe 3. Additional stays 5 extend between and connect the branch pipes 6. By this arrangement the stays 5 are heated and if they are made of a material the expansion of which coincides with that of the elements 2, objectionable stresses in the stays will be avoided. 95

The fans 9 employed to produce a circulation of the air, are disposed between the receptacle 1 and the elements 2 located thereabove, the said fans being preferably pivoted to the steam supply pipe 3 in a 100 horizontal position so as to force the air to flow in upwardly directed currents past the cooler.

- The elements 2 may be arranged in one or more groups, consecutive groups decreasing in size toward the air pump, if desired.
- What we claim as new and desire to secure by Letters Patent of the United States is:—
1. In a locomotive condenser, the combination of a receptacle for steam and water, cooling elements extending transversely thereof, a steam supply pipe connected with said cooling elements, and pipes connecting the receptacle with said steam pipe, said latter connecting pipes together with the steam pipe supporting one end of the cooling elements.
  2. In a locomotive condenser, the combination of a receptacle for steam and water, cooling elements extending transversely thereof and inclining downwardly toward the sides of the condenser, a steam supply pipe connected with said cooling elements, and pipes connecting the receptacle with said steam pipe, the last mentioned connecting pipes together with the steam pipe supporting one end of the cooling elements.
  3. In a locomotive condenser, the combination of a receptacle for steam and water, cooling elements extending transversely thereof, collecting pipes for the water of condensation, a steam supply pipe extending parallel to the condenser and connected with said cooling elements, and pipes connecting the receptacle with said steam pipe, said latter connecting pipes together with the steam pipe supporting one end of the cooling elements.
  4. In a locomotive condenser, the combination of a receptacle for steam and water cooling elements extending transversely thereof and inclining downwardly toward the sides of the condenser, collecting pipes for the water of condensation, a steam supply pipe extending in the longitudinal direction of the condenser and connected with said cooling elements, and pipes connecting the receptacle with said steam pipe, the last mentioned connecting pipes together with the steam pipe supporting one end of the cooling elements.
  5. In a locomotive condenser, the combination of a receptacle for steam and water, cooling elements extending transversely thereof, collecting pipes for the water of condensation extending along the sides of the receptacle, a steam supply pipe extending in the direction of the collecting pipes and connected with said cooling elements, hollow stays connecting said collecting pipes with said steam pipe, and pipes connecting the steam pipe with the receptacle, the connecting pipes together with the steam pipe supporting one end of the cooling elements.
  6. In a locomotive condenser, the combination of a receptacle for steam and water, cooling elements extending transversely thereof, collecting pipes for the water of condensation extending along the sides of the condenser, a steam supply pipe connected with said cooling elements, hollow tubular stays connecting said collecting pipes with said steam pipe, and pipes connecting the steam pipe with the receptacle, the connecting pipes together with the steam pipe supporting one end of the cooling elements.
  7. In a locomotive condenser, the combination of a receptacle for steam and water, cooling elements extending transversely thereof, collecting pipes for the water of condensation extending along the sides of the condenser, a steam supply pipe connected with said cooling elements, hollow stays connecting said collecting pipes with said steam supply pipe, branch pipes connecting the collecting pipes with the receptacle, and pipes connecting the steam supply pipe with the receptacle, said latter connecting pipes together with the branch pipes and the steam pipe forming a supporting structure for the cooling elements.
  8. In a locomotive condenser, the combination of a receptacle for steam and water, cooling elements extending transversely thereof, collecting pipes for the water of condensation extending along the sides of the condenser, a steam supply pipe connected with said cooling elements, branch pipes connecting the collecting pipes with the receptacle, and pipes connecting the steam supply pipe with the receptacle, said latter connecting pipes together with the branch pipes and the steam supply pipe forming a support for the cooling elements.
  9. In a locomotive condenser, the combination of a receptacle for steam and water, cooling elements extending transversely thereof, a steam supply pipe extending in the longitudinal direction of the condenser and connected with said cooling elements, fans pivoted to said steam supply pipe, and pipes connecting the latter with the receptacle.
  10. In a locomotive condenser, the combination of a receptacle for steam and water, cooling elements extending transversely thereof, and inclining downwardly toward the sides of the condenser, a steam supply pipe extending parallel to the condenser and connected with said cooling elements, fans pivoted to said steam supply pipe and pipes connecting the latter with the receptacle.
- In witness whereof we have hereunto set our hands in the presence of two witnesses.
- FREDRIK LJUNGSTRÖM.
ISIDOR BROBERG.
